UNITED STATES PATENT OFFICE.

FRANKLIN H. ELWELL, OF CHICAGO, ILLINOIS.

OIL CUP.

Application filed November 29, 1920. Serial No. 427,123.

To all whom it may concern:

Be it known that I, FRANKLIN H. ELWELL, a citizen of the United States, residing at Chicago, in the county of Cook and State of Illinois, have invented certain new and useful Improvements in Oil Cups, of which the following is a description.

My invention belongs to that general class of devices known as oil cups and has for one of its objects to provide an oil cup which shall continually and constantly feed oil to the part desired with the usual gravitational flow, and which may also be actuated to feed the oil forcibly whenever it is desired to do so.

The invention has among its objects the production of a device of the kind described that is simple, convenient, durable, compact, efficient, dependable, and satisfactory for use wherever found applicable. Many other objects and advantages of the device herein shown and described will be obvious to those skilled in the art to which this invention appertains.

To this end my invention consists in the novel construction, arrangement and combination of parts herein shown and described, and more particularly pointed out in the claims.

In the drawings, wherein like reference characters designate like or similar parts throughout the views;

Fig. 1 is a vertical elevation of my device;

Fig. 2 is a top plan view of the same;

Fig. 3 is a vertical section taken on the line 3—3 of Fig. 2, showing the parts enlarged;

Fig. 4 is a horizontal section on the line 4—4 of Fig. 3; and

Fig. 5 is a horizontal section on the line 5—5 of Fig. 3.

1 represents the oil cup casing, having a reduced threaded extension 2 whereby it may be secured to the cooperating mechanical member which is to be lubricated. The extension 2 is bored axially at 3, said bore being in free communication with the hollow chambered portion or reservoir 4 of the casing, said reservoir being adapted to contain the lubricating fluid.

The bottom or end wall 5 of the casing has an inwardly directed flange 6 thereon, said flange having a bore coaxial with and of the same diameter as the bore 3. Slidably mounted within the bore 3 is a hollow

plunger 7 having a central longitudinal bore therein in free communication with the bore 3 of the extension 2. Apertures 9 are provided in the plungers 7 transversely of the bore 8 at suitable distances apart and communicating therewith, the bore 8 being adapted to receive a suitable absorbent material A, such as felt, wicking, etc., whereby the oil in the reservoir may be drawn through the apertures 9 and into the bore 8 by capillary action. The wick may be additionally held in place in the bore 8 and prevented from dropping by means of a cross pin 9' or its equivalent.

The flange 6 is provided with apertures 10 leading from the reservoir and opening into the bore 3, these openings being normally closed by the plunger 7. A resilient spring 12 is positioned between the head 11 of the plunger and the flange 6, said spring having one end abutting the head 11 and its other end abutting a washer 13 interposed between the spring and the flange 6, the spring 12 tending to keep the plunger 80 against the top of the cup, whereby the plunger body closes the port 10 and the apertures 10 are out of communication with the apertures 9.

A cup packing or washer 14 is secured to the outer end of the plunger, said washer being preferably detachably held in place on the plunger by a removable cap 15.

Spaced from the inner periphery of the casing 1 is a sleeve 16, said sleeve being of less length than the casing and of an internal diameter so as to be in light frictional contact with the outer periphery of the washer 14, one end of said sleeve having a series of slots 17 therein so that the lubricant may flow through the slots exteriorly of the sleeve 16 and freely communicate with the reservoir, a portion of the lubricant remaining on both the inside and the outside of the sleeve.

A removable cover or cap 18 is secured to the casing in any suitable manner as by threading, said cap having a filling hole 19 therein and having a pivotally mounted cover plate 20 which may be swung so as to close the hole 19, or whenever it is desired to fill the reservoir, the hole 19 may be brought into registry with a hole 21 provided in the cover plate.

An actuating rod 22 is slidably movable through the cap 18 and cover 20, said rod bearing upon the cap 15 so as to move the

plunger downwardly of the bore 3, there being a spring 23 interposed between the cover 20 and the enlarged outer end of the actuating rod 22, so as to automatically return 5 the rod to its initial position.

In operation, the reservoir is filled with lubricant through the registering apertures 19 and 21. This lubricant will be absorbed 10 through the bores 8 and 3. Whenever it is desired to feed the lubricant forcibly, the rod 22 is pressed inwardly, which movement will actuate both the plunger and the sleeve 16 so that the sleeve seats on the end wall 5 15 of the casing (see dotted lines in Fig. 3), confining the oil between the sleeve and duct. However, since there is only a frictional contact between the washer 14 and the sleeve 16, the end of the sleeve will remain in contact 20 with the casing while permitting the plunger to continue its downward movement. The ports 10, normally closed, will then be in communication with the ports 9 below the washer 13 and thus will permit the lubricant 25 trapped between the sleeve and the plunger to be forced through the ports 10 into and through the bores 8 and 3 without interrupting the continuity of the capillary oiling action of the plunger. When the rod 22 is 30 released, the spring 23 will retract the rod, and the spring 12 will retract the plunger and move the sleeve into its initial position as shown in full lines in Fig. 3.

Thus it is seen that the sleeve 16 automatically closes the oil passage between it and the reservoir whenever the plunger is actuated, trapping and confining the oil in the reservoir where pressure may be exerted upon it.

If desired, the actuating rod 22 may be dispensed with, and the cover plate 20 pivoted to the cap 18 by a rivet or the like so as to prevent dust and other foreign material from entering the filling hole 19, while 45 allowing the cover to be pivoted so that the holes 19 and 21 are brought into registry whenever it is desired to fill the reservoir. If the actuating rod 22 is omitted, then whenever it is desired to forcibly feed the oil through the duct 3, any suitable instrument may be inserted through the registering openings 19 and 21 and pressed down upon the cap 15. This will actuate the plunger and sleeve in the same manner as by 50 the rod 22. It is quite convenient to use the filling spout of the oil can for the purpose of actuating the plunger when the actuating rod 22 is omitted.

Thus it is seen that there is provided an 60 exceedingly simple, economical and efficient oil cup which will permit of using gravity feeding and yet, whenever it is desired to forcibly feed the lubricant, such may be done without interrupting the continuity of the 65 gravity feed.

Having thus described my invention, it is obvious that various immaterial modifications may be made in the same without departing from the spirit of my invention; hence I do not wish to be understood as 70 limiting myself to the exact form, construction, arrangement and combination of parts herein shown and described, or uses mentioned.

What I claim as new and desire to secure 75 by Letters Patent is:

1. In a device of the kind described and in combination, a casing having an oil reservoir therein and having an oil duct leading therefrom, a hollow plunger in said duct, 80 means for feeding the oil constantly through said plunger and duct, means for feeding the oil forcibly through said plunger and duct, and automatic means for releasing said force feeding means after use but permitting 85 the action of said constant feed.

2. In a device of the kind described and in combination, a casing having an oil reservoir therein and having an oil duct leading therefrom, a hollow plunger slidably mounted in said duct, means for feeding the oil constantly through said plunger and duct, and means for feeding the oil forcibly through said plunger and duct. 90

3. In a device of the kind described and in combination, a casing having an oil reservoir therein and having an oil duct leading therefrom, a hollow plunger slidably in said duct, means for feeding the oil constantly through said plunger and duct, and means for actuating said plunger to feed the oil forcibly through said plunger and duct. 95

4. In a device of the kind described and in combination, a casing having an oil reservoir therein and having an oil duct leading therefrom, a hollow plunger slidable in said duct, means for feeding the oil constantly through said plunger and duct, and means for actuating said plunger to feed the oil forcibly through said plunger and duct 100 independently of said constant feed. 105

5. In a device of the kind described and in combination, a casing having an oil reservoir therein and having an oil duct leading therefrom, said casing also having an 115 aperture leading from said reservoir to said duct, a hollow plunger in said duct and normally closing said aperture, means for constantly feeding the oil from said reservoir through said plunger and duct, and means 120 for actuating said plunger so as to place the bore of said hollow plunger in communication with said aperture, whereby the oil may be forced from said reservoir through said aperture and plunger. 125

6. In a device of the kind described and in combination, a casing having an oil reservoir therein and having an oil duct leading therefrom, an apertured hollow plunger in said duct and extending into said res- 130

ervoir, a sleeve between the plunger and casing wall free to move relative to the end wall of said reservoir so as to seat thereagainst, and means for actuating said plunger and sleeve to seat the sleeve and force the oil in said reservoir through said duct, said plunger being slidable relative to said sleeve.

7. In a device of the kind described and in combination, a casing having an oil reservoir therein and having an oil duct leading therefrom, a hollow plunger in said duct and extending into said reservoir, said plunger having apertures extending transversely of its bore, a sleeve between the plunger and casing wall, said sleeve being slidable relative to said plunger and of a lesser length than the casing so as to be movable longitudinally therein, and means for actuating said plunger and sleeve to seat the sleeve against the end wall of said reservoir and force the oil in said reservoir through said duct.

8. In a device of the kind described and in combination, a casing having an oil reservoir therein and having an oil duct leading therefrom, an apertured hollow plunger in said duct and extending into said reservoir, a sleeve between the plunger and casing wall and free to move relative to the end wall of said reservoir so as to seat thereagainst, said sleeve being spaced from the inner peripheral wall of the casing and having an oil inlet opening at one end, the other end being normally spaced from the casing wall, and means for seating the latter end against the casing and wall and exerting pressure upon the oil so that the oil in the reservoir is forced into the hollow plunger and duct.

9. In a device of the kind described and in combination, a casing having an oil reservoir therein and having an oil duct leading therefrom, a hollow plunger movable in said duct, means for feeding oil constantly through said plunger and duct, a sleeve surrounding said plunger, and means for actuating said

plunger and sleeve to force oil into said duct independently of said constant feed.

10. In a device of the kind described and in combination, a casing having an oil reservoir therein and having an oil duct leading therefrom, a hollow plunger slidable in said duct, said plunger having a central bore communicating with said duct and having apertures in free communication with said central bore, whereby oil may be fed constantly through said duct, and means for forcibly feeding the oil in said reservoir through said plunger independently of said constant feed.

11. In a device of the kind described and in combination, a casing having an oil reservoir therein and having an oil duct leading therefrom, a sleeve in said casing, there being an oil passage between said sleeve and reservoir, and means for closing said passage and exerting pressure upon said oil to force it through said duct.

12. In a device of the kind described and in combination, a casing having an oil reservoir therein and having an oil duct leading therefrom, a sleeve in said casing, there being an oil passage between said sleeve and reservoir, and means for moving said sleeve to close said passage and exerting pressure upon said oil to force it through said duct.

13. In a device of the kind described and in combination, a casing having an oil reservoir therein and having an oil duct leading therefrom, a sleeve in said casing, there being an oil passage between said sleeve and reservoir, and automatically operable means for closing said passage and confining the oil between said sleeve and duct.

In testimony whereof, I have hereunto signed my name in the presence of two subscribing witnesses.

FRANKLIN H. ELWELL.
